ATTY.

UNITED STATES PATENT OFFICE.

JOHN A. TESSMER, OF PROVIDENCE, RHODE ISLAND.

SEAM-STRETCHER.

SPECIFICATION forming part of Letters Patent No. 716,310, dated December 16, 1902.

Application filed December 30, 1901. Serial No. 87,813. (No model.)

To all whom it may concern:

Be it known that I, JOHN A. TESSMER, a citizen of the United States, residing at Providence, in the State of Rhode Island, have invented a new and useful Improvement in Seam-Stretchers for Garments, of which the following is a specification.

My invention consists in an elongated spring-bar provided with pivoted attaching-hooks, which are arranged for engagement with the fabric in opposite directions and are held in their engaged position by means of snap-catches, as hereinafter set forth and claimed.

15 In the accompanying drawings, Figure 1 represents a view of the front side of a flat steel spring-bar provided with my improved engaging hooks. Fig. 2 represents an edge view of the same. Fig. 3 represents a view 20 of the back side of the spring-bar provided with the engaging hooks. Figs. 4 and 5 are detail views of the spring-bar, showing different forms of construction. Fig. 6 represents an enlarged front view of one of the attaching-hooks for engagement with the fabric of the seam. Fig. 7 represents a side view of the same. Fig. 8 represents a rear end view. Fig. 9 represents a front view of the sheet-metal strap for connecting the attaching- 30 hook to the spring-bar. Fig. 10 represents an edge view of the same. Fig. 11 represents a longitudinal section of the seam of the garment, showing the engagement of the attaching-hook therewith. Fig. 12 represents the 35 form of the blank from which the attaching-hook is formed.

In the drawings, A represents a flat spring-bar, of steel or other suitable material, made of the proper length and thickness and preferably provided at its opposite edges with the notches *a a*, the said notches being adapted to receive the turned ears *b b* of the sheet-metal strap B, by means of which the attaching-hook C is secured to the spring-bar A. 45 The strap B is provided with the projecting studs *c c*, made integral with the strap, and upon the studs *c c* is pivoted the attaching-hook C, the said hook being first cut out from sheet metal in the form shown in Fig. 12 and 50 then turned to the form shown in Figs. 6, 7, and 8, the perforations *d d* being adapted to receive the pivot-studs *c c* of the strap B, thus pivoting the attaching-hook to the spring-bar. The attaching-hook C is also 55 provided with the backwardly-extending ears

e e, which being turned inwardly at their ends serve to snap over the edges of the spring-bar A, and thus hold the hook C in its attaching position. The hooks *C C* at the opposite ends of the spring-bar A are arranged for engagement in opposite directions, and in Figs. 1, 2, and 3 three of the hooks are shown in the engaged position, while an end hook is shown in its position preparatory to engagement, the position of the hook when 60 fully engaged with the fabric and held at its rear end by snap engagement with the edges of the spring-bar being shown in Fig. 11, in which *f* represents one of the plies of the seam and *f'* the other, the hook C being 65 turned outward from its position shown at C', Fig. 2, in effecting the required engagement, and when the several hooks are thus engaged with the seam D the spring-bar A will be properly secured to the garment and 70 be capable of ready removal therefrom when desired.

Instead of employing the strap B for effecting the attachment of the hook to the spring-bar the spring-bar itself may be provided with 80 suitable studs *c c*, either by soldering a piece of wire across the spring-bar or by forming the studs integral with the spring-bar, as shown in Fig. 5.

I claim as my invention—

1. The combination of the spring-bar, a hook pivoted thereto at one of its end portions and adapted for detachable engagement with the fabric at the opposite edges of the spring-bar, and the snap means for holding the hook 90 in engagement with the fabric, with an oppositely-directed hook, adapted for engagement with the fabric at the opposite end portion of the spring-bar.

2. The combination of the spring-bar, with 95 the pivoted hooks arranged to turn in opposite directions, for attachment and means for holding the hooks in their engaged positions, substantially as described.

3. The combination of the spring-bar provided with the notches at its edge, and the straps engaging with the notches and provided with the studs, with the oppositely-directed hooks pivoted upon the studs of the straps, and means holding the hooks in their engaged positions, substantially as described.

JOHN A. TESSMER.
